(57) **CLAIM**

I claim the ornamental design for a wheelchair hand rim, as shown and described.

DESCRIPTION

FIG. 1 is a perspective view of a wheelchair hand rim showing my new design;

FIG. 2 is a top plan view thereof;

FIG. 3 is a bottom plan view thereof;

FIG. 4 is a front elevation view thereof;

FIG. 5 is a back elevation view thereof;

FIG. 6 is a top elevation view thereof;

FIG. 7 is a bottom elevation view thereof;

FIG. 8 is a cross-sectional view thereof; and,

FIG. 9 is a perspective view thereof, showing the wheelchair hand rim.

The broken line showing in FIGS. 1-8 is included for the purpose of illustrating the bounds of the claim and forms no part of the claimed design.
